UNITED STATES PATENT OFFICE.

GEORGE J. BROZYK, OF ORLEANS, NEW YORK.

AUTO DIRECTION SIGNAL.

Application filed November 3, 1921. Serial No. 512,694.

To all whom it may concern:

Be it known that I, GEORGE J. BROZYK, a citizen of Servia, residing at Orleans, in the county of Ontario and State of New York, have invented new and useful Improvements 5 in Auto Direction Signals, of which the following is a specification.

This invention relates to signalling devices, particularly to direction signals for 10 vehicles, and has for its object the provision of a manually operated signal device designed to be located at some convenient point upon an automobile, preferably at the upper portion of the dash, and including signal 15 arms adapted to be projected to extend beyond either side of the vehicle whereby to apprise the drivers of following or approaching vehicles, as well as pedestrians and traffic officers, of any contemplated 20 change in the direction of travel of the vehicle equipped with the device.

An important object is the provision of a device of this character provided with spring means normally holding the signal 25 members in inoperative or concealed position, these spring members furthermore operating to return the signal members to normal position after they have been projected to signalling position and the indicated turn 30 has been made.

An additional object is the provision of a device of this character which will be extremely simple and inexpensive in manufacture, easy to install, highly efficient in use, 35 positive in action, durable in service and a general improvement in the art.

With the above and other objects and advantages in view, the invention consists in the details of construction to be hereinafter 40 more fully described and claimed, and illustrated in the accompanying drawings, in which:

Figure 1 is a front elevation of my device with the cover plate or front removed.

Figure 2 is a longitudinal sectional view 45 on the line 2-2 of Figure 1.

Figure 3 is a cross sectional view on the line 3-3 of Figure 1.

Figure 4 is a perspective view of one of 50 the signal members; and

Figure 5 is a perspective view of the other signal member.

Referring more particularly to the drawings I have shown my device as comprising

an elongated casing which is here illustrated 55 as including a back wall 10 to which are secured longitudinal strips 11 arranged in spaced relation to define guides, the casing furthermore including a cover plate or front 12 which is formed with spaced aligned longitudinal slots 13. At its upper and lower sides this casing is provided near its ends with reinforcing metal plates 14 and the ends of the rear wall are provided with apertured ears 15 by means of which the device 60 may be secured upon the vehicle, preferably upon the dash immediately below the wind shield.

Slidably mounted between the guide strips 11 are signal members 16 which are similar 70 in construction and each of which includes an elongated shank 17 slidable between the guide strips 11 and an enlarged head portion 18 which is slidable between the plates 14 and which is inscribed upon its front and 75 rear faces with a suitable legend indicating the direction of a turn to be made. The right hand signal member bears the legend "Right" on both faces while the other bears the legend "Left" on both faces, as clearly 80 shown in the drawings. Carried by the shanks 16 are laterally extending operating knobs 19 which are slidable along the slots 13 and which may be grasped by the operator, whereby the signal members may be selectively projected to indicating position. 85

For normally holding the signal members in concealed or inoperative position, I provide a single coil spring 20 which is located centrally of the casing and which has its 90 ends connected with screw eyes 21, or the like, carried by the confronting ends of the signal members, and it will be apparent that this spring operates to hold both the signal members within the casing with the 95 knobs 19 in engagement with the inner ends of the slots 13. It will be observed that shoulders 22 are formed at the junctures of the heads 18 with the shanks 17 for limiting the inward movement of the signal members 100 in addition to the limit provided by the inner ends of the slots and it may be preferable to provide buffers 23 at the ends of the guide strips 21 for cushioning the shock when the signal members are returned by the 105 spring 20 to their inoperative positions.

Assuming that the device has been constructed and assembled as above described

and suitably mounted upon the dash of a vehicle, and the operator desires to turn either to the right or to the left, he grasps the proper operating knob 19 and projects 5 either the right or left legend bearing signal member into operative position beyond the side of the vehicle so as to be easily visible by the drivers of other vehicles, and in fact by all concerned, so that there will be no 10 doubt as to the contemplated change to be made in the direction of travel. When the operator releases the pressure upon the operating knob the spring 20 will return the signal member to initial concealed position.

15 From the foregoing description and a study of the drawings it will be apparent that I have thus provided an extremely simple and consequently inexpensive signal device which is capable of ready attachment 20 upon a convenient location and which may be operated with the utmost ease. Owing to the fact that there is no automatic mechanism and very few parts, it will be apparent that there is practically nothing to get out of 25 order and that the device should have a long life and efficiently perform all the functions for which it is intended.

While I have shown and described the preferred embodiment of the invention, it is of 30 course to be understood that I reserve the right to make such changes in the form, construction and arrangement of parts as will not depart from the spirit of the invention or the scope of the subjoined claim.

Having thus described my invention, I 35 claim:

A device of the character described comprising an elongated casing including a back wall, longitudinal spaced guide strips secured upon the front face thereof, a cover 40 constituting the front secured to said strips and formed with horizontally aligned spaced longitudinal slots, said strips terminating short of the ends of the back and cover to provide stop shoulders, reinforcing plates 45 secured upon the upper and lower sides of the casing at the ends thereof to cover the open spaces between the outer ends of said strips and the adjacent ends of the casing, a pair of signal members slidably mounted 50 within the casing and including elongated shanks disposed between said guide strips and further including heads slidable between said plates and having shoulders engaging the outer ends of said strips, said 55 signal members bearing direction indicating legends upon their front and rear faces, spring means normally holding said signal members in retracted position, and operating knobs carried by said shanks and slidable 60 through said slots.

In testimony whereof I affix my signature.

George J. Brozyk
